SPRAY CAN HANDLE

Thomas C. Matthews, Hialeah, Fla., assignor to Sun
Engineering Co., a corporation of Florida

Filed Oct. 19, 1965, Ser. No. 87,601

Term of patent 14 years

(Cl. D58—26)

FIG. 1 is a top, front perspective view of a spray can handle showing my new design, a fragmentary showing of a spray can being for illustrative purposes only; and FIG. 2 is a bottom, rear perspective view.

I claim:

The ornamental design for a spray can handle, substantially as shown and described.
